UNITED STATES PATENT OFFICE.

PIERRE AMET, OF PARIS, FRANCE.

SEPARATOR.

Application filed July 16, 1926, Serial No. 122,996, and in France July 30, 1925.

It is a matter of common knowledge that gasoline for use with explosion engines should be freed from any water and solid particles which it may contain, and that the provision 5 made for such treatment in roadside filling apparatus is often inadequate and even poor.

The object of my invention is to provide a separator chiefly intended for roadside gasoline dispensing devices but, in a general 10 way, applicable to any other dispensing apparatus. My separator is designed for the purpose of automatically separating from the gasoline wherein they may happen to be contained water and solid particles.

15 In order to make my invention more clearly understood I have illustrated, as an example, an embodiment of the device which is the object thereof in and by the accompanying drawing wherein:

20 Figure 1 is a vertical section of a separator constructed according to my invention;

Figure 2 is a horizontal section of the same.

The india rubber hose *a* that leads from 25 the dispensing apparatus is connected with the separator proper by means of a detachable union-handle *b* adapted to be securely fitted on the end of a tube or nipple *c* which is integral with the separator proper. On 30 reaching the separator gasoline enters an annular chamber *d* through which it flows in the direction indicated by arrows on Figure 2. Said chamber comprises baffles *e* formed with apertures *f* that increase gradually in 35 diameter from the inlet to the outlet thereof.

The chamber *d* is designed to decrease the speed at which gasoline enters the separator, the gasoline being always full load on reaching the separator. At the same time, owing 40 to baffles *e*, whatever solid particles may be contained in the gasoline settle on the bottom of the chamber and are not carried into circulation.

Gasoline issues from the chamber through 45 aperture *g* and descends through central tube *h* to the space between two plates *i* throughout which it spreads thereby effecting separation from the gasoline of any water contained in it, the gasoline rising into the body 50 *j* of the separator, while the water descends into part *k*.

Thus rid of water and of any solid particles which it may have contained, the gasoline issues from container *j* through a tube *l* and 55 passes through valve *m* and orifice *o*, into a

second chamber *p* concentric with the first one and disposed within the same and, like it, comprising baffles formed with openings gradually increasing in diameter from the gasoline inlet to its outlet. Gasoline issues 60 from said second chamber *p* through an aperture *q* in order to arrive into an upper tank *r* wherefrom it descends through an annular space or passage *s* which surrounds container *j* in order finally to flow into a tube 65 or nozzle *t* which leads to the filling hole of the gasoline tank.

The water that collects at *k* ultimately, that is to say, whenever in sufficient quantity, raises a float *u* which acts through a suitable 70 stem or rod *v*, the upper part of which is connected with valve *m* while its lower part connected with a ball shaped valve *z*. When, owing to float *u* rising, valve *m* is closed and valve *z* is open, which the operator can read 75 from a pointer visible from outside and actuated by rod *v*, the water can be discharged from the apparatus by opening cock *y*, whereupon float *u* will sink and restore the filter to normal working condition. 80

The casing or body of the separator may be made of metal with transparent windows, or entirely made of transparent material in order to enable gasoline consumers to watch its operation. The separator can be constantly filled with gasoline and the quantity passing through will be the one shown by the measuring instruments of the dispensing apparatus itself. The separator being full 85 on being set working, will remain full at 90 the end of use and will simply have been traversed by the quantity of gasoline delivered by the dispensing apparatus.

Handle *b* may constitute a chamber with filtering material for the gasoline to permeate 95 through.

I claim as my invention:

1. A gasoline separator, comprising a casing having an inlet and an outlet for the gasoline; and concentric outer and inner annular settling chambers within the casing in communication with each other, and also in communication, respectively, with said inlet and outlet, each chamber having a plurality of internal radial baffles formed with apertures. 100

2. A gasoline separator, comprising a casing having an inlet and an outlet for the gasoline; and concentric outer and inner annular settling chambers disposed in a common 105 110

horizontal plane within the casing in communication with each other, and also in communication, respectively, with said inlet and outlet, each chamber having a plurality of 5 internal radial baffles formed with apertures.

3. A gasoline separator, comprising a casing having an inlet and an outlet for the gasoline; and concentric outer and inner annular settling chambers within the casing in 10 communication with each other, and also in communication, respectively, with said inlet and outlet, each chamber having a plurality of internal radial baffles formed with apertures which increase in size in the successive baffles 15 from the inlet to the outlet of the chamber.

4. A gasoline separator, comprising a casing having an inlet and an outlet for the gasoline; and concentric outer and inner annular settling chambers disposed in a common 20 horizontal plane within the casing in communication with each other, and also in communication, respectively, with said inlet and outlet, each chamber having a plurality of internal radial baffles formed with apertures 25 which increase in size in the successive baffles from the inlet to the outlet of the chamber.

5. A gasoline separator, comprising a casing having an inlet for gasoline and separate outlets for gasoline and water; concentric 30 outer and inner annular settling chambers in the casing, the outer chamber having its inlet in communication with the gasoline inlet, and the inner chamber having its outlet in communication with the gasoline outlet; 35 means within said casing communicating with the outlet of the outer settling chamber for separating the water contained in the gasoline from the gasoline itself; and separate collecting chambers in said casing for the 40 gasoline and water, both collecting chambers

being in communication with said separating means, and the gasoline collecting chamber having an outlet leading to the inner settling chamber, while the water-collecting chamber has an outlet leading to the water outlet. 45

6. A gasoline separator, according to claim 5, in which both settling chambers are provided with internal radial baffles having apertures formed therethrough. 50

7. A gasoline separator, according to claim 5, in which both settling chambers are provided with internal radial baffles having apertures formed therethrough which increase in size in the successive baffles from the inlet to the outlet of the respective chambers. 55

8. A gasoline separator, comprising a casing having an inlet for gasoline and separate outlets for gasoline and water; concentric outer and inner annular settling chambers in the casing, the outer chamber having its inlet in communication with the gasoline inlet, and the inner chamber having its outlet in communication with the gasoline outlet; means within said casing communicating with the outlet of the outer settling chamber for separating the water contained in the gasoline from the gasoline itself; separate collecting chambers in said casing for the gasoline and water, both collecting chambers being in inlet communication with said separating means, 60 and the gasoline collecting chamber having an outlet leading to the inner settling chamber, while the water-collecting chamber has an outlet leading to the water outlet; and a double-acting valve device for simultaneously 65 opening communication between the water collecting chamber and outlet and closing the entrance to the gasoline collecting chamber. 70

In testimony whereof I affix my signature. 75
PIERRE AMET.
